UNITED STATES PATENT OFFICE.

JOHN L. CREVELING, OF NEW YORK, N. Y., ASSIGNOR TO SAFETY CAR HEATING & LIGHTING COMPANY, A CORPORATION OF NEW JERSEY.

TRAIN FAN SYSTEM.

No. 905,292.

Specification of Letters Patent.

Patented Dec. 1, 1908.

Application filed October 3, 1901. Serial No. 77,373.

To all whom it may concern:

Be it known that I, JOHN L. CREVELING, a citizen of the United States, residing at the borough of Manhattan, city, county, and State of New York, have invented certain new and useful Improvements in Train Fan Systems, of which the following is a specification.

My invention relates to pneumatic fan systems, and for the purpose of complying with the statute will be described with special reference to train fan systems, it being understood however, that the invention is not limited thereto, but that the invention is so described in order to distinctly and definitely set forth one embodiment thereof.

In the accompanying drawing I have shown in Figure I a sufficient number of parts of a railway train to illustrate one embodiment of my invention. In Fig. II, I have shown the details of the arrangement of the auxiliary reservoir upon each car.

In the drawing A represents a locomotive, B the tender, and C the first car of the train of which there may be several.

Mounted upon the locomotive is a suitable air-pump *a* receiving steam from the locomotive boiler through the connection *b* and preferably exhausting into the stack through the exhaust *c*. Leading from the air-cylinder of the compression pump *a* is a train line *d*, which communicates through suitable couplings and flexible connection *e* with a coil of piping *f* herein shown as located in the tender B. Carried upon the tender is a reservoir *g* having a fluid seal *s* beneath which the delivery pipe *i* of the coil *f* dips.

Leading from the upper portion of the reservoir *g* is a continuous train-pipe *d* which leads to auxiliary reservoirs *h* having check-valves *n* shown beneath the floor of the car, carried by the respective cars.

The reservoirs *g* and *h* are preferably provided with drip-cocks *k*, and leading from the respective auxiliary reservoirs *h* are pipes *l* in each car which lead to pneumatic fans carried upon the car.

A suitable regulator *o* is interposed in the steam connection *b* of the pump *a* and is connected by pipe *p* with the train pipe *d*. The function of this regulator is to control by means of the air-pressure the admission of steam to the air compressor *a* so that when the air-pressure falls in the system the regulator *o* will operate to open a valve to

admit steam to the air-compressor so that the pressure will be pumped up.

The air from the air-compressor passing through the train pipe *d* traverses the coil or condenser *f* and is thereby cooled and 60 deposits moisture in the condenser *f* and the reservoir *g*. The air passes through the water-seal in the reservoir *g* and is thereby scoured or cleansed. The air passes from the reservoir *g* to the auxiliary reservoirs 65 *h* in each car and thence is supplied to the fans *m* in the cars. The reservoir *g* serves to trap the moisture in a very efficient manner and the air passes to the auxiliary reservoirs clean and dry, it being quite essential 70 that the exhaust shall be clean and dry, otherwise the air discharged into the cars by the fans will scatter dirt and moisture and thereby ruin the furnishings.

The heat given off by the air when it is 75 cooled in the tender is useful in that it tends to heat the feed-water of the locomotive.

It will be understood that the location of the various parts is not essential. 80

Having described my invention what I claim and desire to secure by Letters Patent is:

1. In a train ventilating system, in combination, an air compressor carried by the locomotive and driven by steam from the boiler, a coil located in the tender of the locomotive through which said compressed air passes adapted for condensing moisture therefrom, means carried by said tender for 85 scouring the compressed air when the same has been delivered from said condensing coil, said scouring means being also adapted to receive the drippings from said condensing coil, a storage tank located upon each 90 car of the train, a train pipe leading from said scouring means and communicating with each of said tanks; a pneumatically driven fan carried by each of said cars, and a conducting conduit leading from each of 95 said storage tanks to one of said fans.

2. In a train ventilating system, in combination, an air compressor carried by the locomotive and driven by steam from the boiler, a condensing coil carried by the 100 tender of the locomotive and communicating with said compressor whereby the compressed air may have the moisture condensed therefrom, scouring means carried by said tender and communicating with said con- 105

110

densing coil, a storage tank carried by each car of the train, a train pipe leading from said scouring means and communicating with each of said tanks, a pneumatically 5 driven fan carried by each of said cars, and a conduit leading from each tank to one of said fans, each of said tanks intervening between the train pipe and its associated conduit.

In testimony whereof, I have signed my name to this specification in the presence of two subscribing witnesses, this 12th day of September, 1901.

JOHN L. CREVELING.
